UNITED STATES PATENT OFFICE.

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK.

PRODUCTION OF MODULATED WAVES.

Application filed July 17, 1922. Serial No. 575,591.

The present invention relates to the production of modulated waves, and more particularly to the production of high frequency oscillations modulated in accordance with 5 relatively low frequency signaling or control currents.

This invention is related to the system and method of modulation disclosed in my prior Patent, No. 1,442,147 dated January 16, 0 1923, in which the specific disclosure has a plurality of discharge tubes supplied with discharge current from a common source, one 0 of said discharge tubes serving to supply the high frequency oscillations, and the signaling 5 variations being impressed on the other tube. The present invention involves advantageous features not included in the specific disclosure of my prior application and these will be pointed out hereinafter.

0 In the specific arrangement disclosed in my prior application referred to, two separate electron discharge tubes of the audion type have their plates or anodes connected together and their filaments or cathodes connected 5 together, while between the common plate connection and the common filament connection, there is a path including a high impedance and a source of space discharge current for both tubes. Variations in the 0 space current of one tube produce corresponding variations in the space current of the other tube, said impedance preventing these variations from passing through it. By arranging one of said tubes to supply 5 high frequency oscillations to any desired system, and controlling the space current of the other tube directly by signals, for example, the corresponding variations in the high-frequency tube cause the supplied 0 waves to be modulated in accordance with the signals impressed on the other tube.

Experience has shown that in some cases it is advantageous to use a different anode voltage for the tube or device which furnishes the high frequency oscillations from that used for the tube or device upon which the signals are impressed. Particularly if discharge tubes of the same type and dimensions are used for both purposes it has been 0 found that to secure the most effective degree of modulation of the high frequency wave, a higher anode voltage should be used

for the tube upon which the signals are impressed than for that which supplies the high frequency oscillations.

55

The present invention enables these advantages to be attained in that it provides a modulating arrangement in which separate sources of discharge current are employed for the separate discharge devices respectively from which the modulated oscillations are supplied and upon which the signals are impressed.

60

In the arrangement according to the invention to be described more fully herein-after, the space current circuits of a plurality of discharge devices upon certain of which the signal variations are impressed and from other of which the modulated oscillations are supplied, are associated with each other, 70 and two separate sources of discharge current are provided for the devices which fulfill these two functions. The two space current circuits are connected by paths of low impedance for signaling variations. When 75 signals are being transmitted, variations in the space current of the first circuit set up a signal wave electromotive force in an inductance in that circuit, and this electromotive force is accordingly applied to the other space current circuit to cause a complementary current variation therein relative to the variation in the first circuit and to effect corresponding variations in amplitude 80 of the outgoing oscillations.

85

The various features of the invention will be apparent from the following description of typical circuits illustrated in the accompanying drawings, in which Figs. 1, 2 and 3 are schematic representations of transmitting circuits embodying the invention, and Fig. 4 shows an alternative arrangement capable of use in the circuits of the other figures.

90

In Fig. 1 the transmission circuit 1, which is specifically shown as an antenna but which may equally well be any desired type of circuit such as a line, is supplied with carrier oscillations from the source 2, and the amplitude of these oscillations is varied under control of the device 3 which is supplied with signaling frequency variations from the circuit 4. The circuit 4 is specifically shown as a microphone circuit containing bat-

100

ter 5, microphone 6, and the primary of the transformer 7. Each of the devices 2 and 3 may be an electron discharge device preferably highly evacuated and containing an electron-emitting cathode such as a heated filament, an anode, and a grid or impedance control element the general construction of such devices being now well known in the art. The discharge tube 2 is arranged in the circuit of this figure as a generator of oscillations and for this purpose has both its plate circuit 8 and its grid circuit 9 coupled to the antenna 1. Either or both the antenna and the plate circuit may have provision for tuning, as by the constants of the antenna and by the condenser 10. By thus coupling the plate circuit 8 and the grid circuit 9 to the antenna, the tube 2 is made to generate sustained oscillations in the antenna for transmission. If desired, amplification for the waves from the source 2 may be provided before transmission, if the source 2 is of insufficient power. Other types of circuit connection may be used for causing the tube 2 to generate oscillations and supply them to the antenna, a number of suitable connections being known in the art. Space current for the oscillator 2 is supplied from the source 11 which may be a battery or a generator of any suitable type. Included in the supply path from source 11 is an impedance 12, the action of which will be explained later. The discharge device 3, upon which the signaling variations from circuit 4 are impressed, has its space current supplied from source 13, and its supply circuit also includes the impedance 12. As stated, the voltage of source 13 may be the same as, or different from that of source 11, depending on the type of tubes used and possibly other conditions. When tubes 2 and 3 are of the same type and have the same anode-cathode impedance it has been found advantageous to make the voltage of source 13 of the order of 25% or 50% higher than that of source 11. It is advantageous to make the impedance of the coil 12 at the most sensitive signaling frequency (in the case of speech about 800 or 1000 cycles) greater than the plate-circuit impedance of the oscillator when it is oscillating at a steady amplitude, although the circuit works well if the coil impedance is only about equal to the oscillator impedance. By way of example it may be stated that if the D. C. impedance between the cathode and anode of the oscillator tube 2 when it is oscillating is 10,000 ohms, the impedance of 12 for the most sensitive signal frequency, say 1000 cycles, is preferably the same or greater, and in case this impedance of coil 12 is practically entirely inductive it may be 1.0 or 1.25 henry. However, the impedance of 12 may also consist partly or largely of

ohmic resistance. The plate impedance of tube 3 under its operating conditions would in the case of the above values be about 7000 ohms, on the assumption that it is the same type of tube as 2. These values are given by way of example only and are not to be taken as limiting the invention. The high frequency choke 14 freely transmits current variations of signaling frequency but offers great opposition to the passage 75 through it of variations of the frequency of oscillation of the source 2. The waves generated by the source 2 are therefore prevented from being shunted through the tube 3 or any distributed capacity of choke 80 12 and its associated circuits and are confined principally to the circuits of the tube 2 and antenna 1. Blocking condenser 16 prevents the short-circuiting of battery 11 through the inductance winding of circuit 85 8. The cathodes of tubes 2 and 3 may be provided with high frequency grounds, as by directly grounding one and connecting the other through a small condenser 15 to ground. To secure the advantages of separate space current sources for the devices 2 and 3 of this figure, it is evident that both cathodes are not to be conductively connected to ground. 90

It is within the scope of the invention to use in place of either or both of the single tubes 2 or 3 a plurality of tubes in parallel, arranged in each instance, for example, as shown in U. S. Patent No. 1,388,450 to Col- 95 pitts et al., dated August 23, 1921. The 100 combination of resistance and capacity indicated at 19 is for the purpose of fixing the average potential of the grid in a manner described in my prior Patent No. 1,413,732, April 25, 1922. 105

In operation, continuous oscillations are produced in the transmission circuit 1 by the well-known action of the tube 2. So long as no sounds are produced before the microphone 6, these oscillations continue 110 with constant and unvarying amplitude, since the circuit elements and the quantities which determine the steady operation of the source 2 remain unchanged. As described above, however, the plate circuits of the 115 tubes 2 and 3 are interlinked in such a way that variations in the current through the tube 3, in accordance with speech for example, are accompanied by corresponding variations in the space current of the oscillator 2 and the amplitude of the oscillations produced in the antenna 1 varies accordingly. Thus, as the impedance of tube 3 varies in accordance with sound waves, for example, incident upon microphone 6, the current through the tube 3 from the source 13 is caused to vary and the choke 12 generates an electromotive force between the points 17 and 18 of such direction as either 120 to add to or subtract from the voltage of 125 130

sources 11 and 13. Thus a momentary increase in the impedance of tube 3 causes an impulse of increased space current in the oscillator tube 2, and a momentary decrease in impedance of the tube 3 causes a decrease in the space current of the tube 2. The sum of the space currents in the tubes 2 and 3 is from instant to instant substantially constant.

The circuit of Fig. 2 is identical with that of Fig. 1 except as regards the ground connection (and the difference in this is immaterial) and the connection for supplying space current to the oscillator tube 2. In Fig. 2 the space current supply leads for the tube 2 are connected directly to opposite terminals of the blocking condenser 16, so that this condenser not only prevents short-circuiting the space current source 11 but acts as a high frequency shunt of practically zero impedance, on account of its relatively large size, across the tube 3 so that the carrier oscillations are confined to the circuits of the generator 2. With this arrangement the high frequency choke 14 is unnecessary and may be omitted. The condenser 16 of this figure, while large enough to transmit freely the high frequency oscillations from source 2, is still sufficiently small to offer high impedance to currents of signal frequency so that they are caused to pass through the tube 2.

In Fig. 3 two choke impedances 20 and 21 are provided for the two space current circuits of the tubes 3 and 2, and the corresponding terminals of these chokes are joined by low impedance paths which might be constituted in any appropriate manner but are shown as comprising the condensers 22 and 23 respectively. If instead of these condensers, conductance paths of low impedance were used the circuit would reduce to substantially that of Fig. 1 with two chokes in parallel in place of the one choke 12. This type of connection admits of both filaments of tubes 2 and 3 being grounded directly, and also permits a single direct current source of heating current to be used for both filaments, as shown.

The operation of the circuit of Fig. 3 may be explained similarly to that described above for the circuit of Fig. 1. The condensers 22 and 23 permit the free passage of current variations of the signaling frequency. A change in the current through the tube 3, and hence through the choke 20, causes the choke 20 to generate a momentary electromotive force between its terminals, and this is communicated by the condensers 22 and 23 to terminals of the choke 21 and to the tube 2 in parallel thereto. The choke 21 offers great opposition to a change in the current through it with the result that the electromotive force communicated from the choke 20 is relieved by a change in the space cur-

rent through the tube 2. The actual space current through the tube 2 is therefore greater or less depending on whether the superposed electromotive force aids or opposes that of source 11.

In the case of each of the Figs. 1, 2 and 3, the tube two is shown and has been described as provided with circuits for causing it to generate the high frequency oscillations transmitted by the circuit 1. In each case, however, a separate source of waves may be associated with the tube 2 for supplying the high frequency waves for transmission. One such arrangement is shown in Fig. 4, in which the source 25 is associated with the grid circuit of tube 2 through the transformer coupling 26. The arrangement of Fig. 4 may be substituted for that portion of any of the circuits of the other figures, lying to the right of the line *ab*. Suitable ground connection (not shown) to the cathode of tube 2 may be made by a condenser such as 15, or conductively in case the cathode of tube 3 is connected through a condenser to ground, as hereinbefore explained, or in case the type of circuit shown in Fig. 3 is used. In this arrangement the tube 2 repeats the waves furnished by the source 25, and preferably amplifies them. It also controls the amplitude of the waves transmitted, due to changes in its space current caused by changes in impedance of the tube 3 as described in connection with the other figures.

The invention is not to be construed as limited to the specific circuit arrangements that have been shown and described in detail, but only by the scope of the appended claims.

What is claimed is:

1. A modulation system of the constant current type comprising electric discharge devices having cathodes, anodes and control electrodes, means for impressing carrier frequency oscillations on one of said devices, means for impressing modulating oscillations upon another of said devices, said two devices having such characteristics as to adapt them for different space current voltages whereby high modulation efficiency may be obtained, separate space current sources connected respectively to said two devices and having electromotive forces suitable for the device to which they are respectively connected, and means for maintaining the sum of the space currents of said two devices effectively constant at the frequencies of the modulating waves while permitting modulating frequency variations of opposite sign in the individual space currents.

2. A modulation system of the constant current type comprising electric discharge devices each having a cathode, an anode and control electrode, means for controlling the space current of one of said devices by carrier frequency oscillations, means for con-

- trolling the space current of another of said devices by modulating oscillations, said two devices having such characteristics as to adapt them for different space current voltages whereby high modulation efficiency may be obtained, separate space current sources connected respectively to said two devices and having electromotive forces suitable for the respective devices to which they are connected, and means for maintaining the sum of the space currents of all of said devices effectively constant at frequencies of the order of those of the modulating oscillations while permitting modulating frequency variations of opposite sign in the individual space currents of said two devices.
3. In combination, a pair of electron discharge tubes, each having a cathode, an anode, a grid, an anode circuit and a grid circuit; a separate source of space current for each of said tubes; means for supplying high frequency oscillations to the grid circuit of one of said tubes and relatively low frequency signaling waves to the grid circuit of the other of said tubes; high inductance means between said sources of space current and said anodes arranged with respect to said anode circuits for causing the variations of signaling frequency in the space discharge currents of said tubes to be substantially complementary to each other whereby the high frequency oscillations in said one tube are modulated in accordance with the signaling waves impressed on the other tube.
4. In combination, two electron discharge devices, each having a cathode, an anode and a grid, anode circuits and grid circuits therefor, a separate source of space current for each device connected between its cathode and anode, means in circuit with said sources for keeping the total current supplied to said anodes substantially constant as regards variations of signaling frequency, means to supply signaling frequency variations to the grid circuit of one of said devices and high frequency oscillations to the grid circuit of the other device and connections for impressing signaling frequency variations from the anode circuit of the first device upon the anode circuit of the second device for modulating the high frequency oscillations in accordance with signals.
5. In combination, two electron discharge tubes, each having a cathode, an anode, a grid, an anode circuit and a grid circuit; means for impressing signaling variations on the grid circuit of one tube independent of the other grid circuit; means for impressing sustained high frequency waves on the grid circuit of the other tube independent of the first grid circuit; separate sources of space current for said anodes and means associating said anode circuits for keeping the sum of the currents supplied to the two

anodes substantially constant as regards variations of signaling frequency.

6. In combination, an electron discharge tube oscillator; a second electron discharge tube; each of said tubes having a cathode, an anode, a control electrode and a source of space current; means to maintain constant as regards variations of signaling frequency the sum of the currents supplied from said sources of current to said discharge tubes; and means to vary the space current of said second discharge tube under control of signals to be transmitted.

7. In combination, a plurality of electron discharge devices each having space discharge electrodes, a transmission circuit, connections for utilizing one of said devices to supply sustained high frequency oscillations to said transmission circuit, a source of discharge current for said one device, a separate source of discharge current for another of said devices, means to vary the discharge current through said last-mentioned discharge device in accordance with signals to be transmitted, and means to maintain the sum of the discharge currents supplied to said devices constant as regards variations of signaling frequency.

8. In combination, a plurality of electron discharge devices, circuits for supplying discharge current thereto, a transmission circuit, connections for utilizing one of said devices to supply high frequency oscillations to said transmission circuit, a source of discharge current for said one device, a source of discharge current for another of said devices, means to vary the discharge current through said last-mentioned device in accordance with signals to be transmitted, and means interlinking the discharge current supply circuits of said devices for causing a decrease or increase in the discharge current supplied to said first-mentioned device when an increase or decrease, respectively, occurs in the discharge current of the second-mentioned device.

9. In combination, an electron discharge device, a source of discharge current for supplying said device, a second electron discharge device, a source of discharge current for supplying said second device, said sources being of respectively different voltage, connections for utilizing the first of said devices to transmit high frequency oscillations, means to vary the discharge current through the second device at a relatively low frequency rate compared with the frequency of said high frequency oscillations, and means for causing the supply of discharge current to said first discharge device to vary in a manner substantially complementary to the variations in the discharge current through the second device, whereby low frequency amplitude variations are produced in said high frequency oscillations.

10. An arrangement as claimed in claim 9, the source of discharge current for said second discharge device being of higher voltage than the source of discharge current for the said first discharge device.

11. In combination, an electron discharge tube having a cathode and an anode, a source of discharge current and a circuit for supplying current from said source to said tube, connections for utilizing said tube to transmit high frequency oscillations, a second discharge tube having a cathode and an anode, another source of discharge current and a circuit for supplying discharge current from said latter source to said second tube, means to impress signal waves on said second tube, a path connecting said anodes and capable of freely transmitting currents of signaling frequency, a path connecting said cathodes and capable of freely transmitting currents of signaling frequency, each of said current supply circuits including a high inductance portion offering very great opposition to the passage through it of currents of signaling frequency whereby current variations of signal frequency in said second tube are caused to pass through said first tube and vary the amplitude of the high frequency oscillations transmitted.

12. In combination two circuits, each of said circuits being composed in part of an electron discharge space and a source of space discharge current, inductance choking means associated with said circuits, said circuits having a connection with each other at each side of said means, and means individual to one of said circuits for producing variations in the discharge current in said one circuit of a frequency too high to pass readily through said choking means, whereby variations are produced in the discharge current of the other circuit.

13. In combination two circuits, each of said circuits including an electron discharge space and a source of discharge current individual thereto, means individual to one of

said circuits for producing variations in the discharge current in said one circuit, said circuits having a connection with each other at one side of said sources of discharge current and at another point, and inductance choking means included in said two circuits between said connections, of such high inductance as substantially to prevent the passage therethrough of said variations.

14. In a modulating circuit a plurality of electron discharge tubes, circuit arrangements for said tubes including means to impress signals on certain of said tubes and means to use other of said tubes to supply carrier oscillations modulated in accordance with said signals, said circuit arrangements also including a path, a portion of which at least is individual to the certain of said tubes upon which the signals are impressed, said portion including a source of space discharge current, said circuit arrangements also including a path a portion of which is individual to the other of said tubes, said portion including a source of space discharge current, and inductive choking means included between said sources of discharge current and the discharge spaces of said tubes, having an inductance of such magnitude as substantially to prevent the passage through said choking means of current variations of the signaling frequency, said circuit arrangements also including a path exclusive of said choking means and extending through the discharge spaces of said certain of said tubes and said other of said tubes in series.

15. The arrangement specified in claim 14 in which said inductive choking means comprises two inductors and means whereby they are substantially in parallel with respect to current variations of the signaling frequency but individual, respectively, to said certain tubes and said other tubes as regards unvarying current.

In witness whereof, I hereunto subscribe my name this 13th day of July, A. D. 1922.

RAYMOND A. HEISING.
